UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A HANDLE FOR SPOONS, &c.

SPECIFICATION forming part of Design No. 29,261, dated August 23, 1898.

Application filed July 29, 1898. Serial No. 687,217. Term of patent 14 years.

To all whom it may concern:

Be it known that I, WILLIAM C. CODMAN, of Providence, in the county of Providence and State of Rhode Island, have invented and produced a new and original Design for the Handles of Spoons, Forks, and Similar Articles, of which the following is a specification, reference being had to the accompanying drawings, forming part thereof.

10 Figure 1 is a view of the front or obverse side of the handle, showing my design attached to the bowl of a spoon, the tines of a fork being indicated in broken lines. Fig. 2 is a view of the reverse side of the same. Fig. 15 3 is a transverse section of the upper part of the handle.

10 The leading feature of my design consists in the peculiar outline and ornamentation of the upper end of the obverse side of the handle, representing the conventional form of a baronial shield having a raised marginal bead surmounted by the head of a lion and inclosed by oppositely-disposed scrolls the foliations of which extend along the sides of the shield.

25 On the obverse side of the handle, 4 indicates a convex panel inclosed by the raised bead 5. The panel is widest near its upper end, and the curved outline terminates in a point at its lower end. The panel is surrounded by the representation of the head of a lion 6. The rolled scrolls 7 7 extend obliquely in opposite directions from the lion-head and over the edge of the oblique upper end of the panel 4. The foliations 8 8 extend 30 from the scrolls 7 7 along the edge of the handle on each side of the panel. The foliated scrolls 9 9 inclose the smaller convex panel

10. At the junction of the blade A of the handle with the stem B the foliated scrolls 11 11 inclose the floral ornament 12.

40 The stem B of the handle is ornamented by the raised marginal beads 13 13, inclosing at the upper end the pendent floral ornament 14. At the junction of the stem B of the handle with the article to which it is attached 45 the foliated scroll ornaments 15 inclose the shell ornament 16. On the reverse side of the handle the marginal outline of the handle is preserved, the back of the lion-head at the upper end of the handle is formed into 50 the conventional honeysuckle ornament, the foliated scrolls extend along the margin of the blade of the handle, intervening with the scrolls on the back of the foliated scrolls 9 9, and foliated scrolls similar to the scrolls 11 55 extend from the intersection of the blade with the stem of the handle. Raised beads form the margin of the stem, and the ornamentation at the lower end of the obverse side of the handle is extended over the article to 60 which the handle is attached.

Having thus described my invention, what I claim as new, and desire to secure by Letters Patent, is—

65 The design for the handle of spoons, forks and similar articles substantially as herein shown and described.

In witness whereof I have hereunto set my hand.

WILLIAM C. CODMAN.
